UNITED STATES PATENT OFFICE

EARL W. ROBERTS, OF DETROIT, MICHIGAN, ASSIGNOR TO ROBERTS BRASS MANUFACTURING COMPANY, OF DETROIT, MICHIGAN, A CORPORATION OF MICHIGAN

ADJUSTABLE SUPPORT FOR GAS LIGHTERS AND THE LIKE

Application filed October 28, 1929. Serial No. 403,055.

This invention relates generally to supports and refers more particularly to means for supporting gas lighter assemblies and the like in adjusted position relative to the gas burners of a stove.

One of the essential objects of the invention is to provide a support of the type described in which a bridge extending between the usual gas manifold and one of the usual 10 transversely extending burner supporting rods carries the lighter assembly.

Another object is to provide a support in which the means for conducting gas to the pilot burner of the lighter assembly constitutes a part of the bridge aforesaid.

A further object is to provide a support in which one end of the bridge is movable longitudinally of the burner supporting rod whereby the lighter assembly may be positioned properly in a horizontal plane relative to the gas burners.

Another object is to provide a support in which portions of the bridge are constructed of relatively soft material that may be bent 25 or re-shaped so that the lighter assembly may be adjusted properly in an upright plane relative to the burners.

With the above and other objects in view the invention consists of certain novel features of construction, combinations and arrangements of parts, that will be hereinafter more fully described, and particularly pointed out in the appended claim.

In the accompanying drawings:

35. Figure 1 is a fragmentary perspective view of a stove with a gas lighter support embodying my invention applied thereto;

Figure 2 is a sectional view taken on the line 2—2 of Figure 1;

40. Figure 3 is a top plan view of the support and associated parts.

Referring now to the drawings, 1 is a gas burner compartment of a suitable stove, 2 and 3 are the usual transversely extending burner 45 supporting rods terminally connected to the side walls of the compartment, 4 is a gas manifold in front of said compartment, 5, 6, 7 and 8 are conventional gas burners within the compartment and resting on the supporting rods, 8, 9, 10 and 11 are the usual mixing

tubes extending from the manifold to the burners, and 12 are valves controlling the supply of gas from the manifold to the mixing tubes.

In the present instance the burners are 55 lighted automatically when the valves 12 are open, and this has been accomplished by providing a gas burner lighter assembly A in which 13 is a pilot burner, 14 is a tube for conducting gas from the manifold 4 to the 60 pilot burner, 15 is a cup-shaped housing on the pilot burner casing 13' and adapted to receive the flame issuing from the pilot burner, 16 are tubes projecting radially from the housing 15 and overlapping lateral jets 65 17 in the main gas burners, 18 is a cover for the housing and 19 is a frustro-conical shield on the housing below the tubes for preventing foreign matter such as fluids from entering the openings 20 and lateral orifice 21 70 in the housing 15 and pilot burner 13 respectively.

In use, when the valves 12 are opened, gas from the jets 17 in the main burners will be conducted by the tubes 16 to the housing 15 75 where it will be ignited by the flame from the pilot burner 13 whereupon the resulting flame will be conducted back through the tubes 16 to the upwardly opening jets 25 in the main burners and will automatically light 80 the same.

With constructions of this kind it is desirable to have some means by which the lighter assembly A may be positioned properly and adjusted relative to the burners and 85 it will be observed that I have accomplished this by providing the assembly with a supporting bridge B that extends between the manifold 4 and the rod 3. Preferably the tube 14 and pilot burner casing 13' constitute 90 parts of this bridge, and the remaining parts comprise a rod 27 and a supporting block 28. As shown, the rod 27 projects rearwardly from the pilot burner casing 13' in substantial alignment with the tube 14 and is slidably 95 received in an opening 29 in the block 28. This block in turn is slidably mounted upon the rod 3 whereby the bridge B and lighter assembly A may, as a unit, be adjusted horizontally relative to the burners. Any suit- 100

able means such as the set screws 30 and 31 may be used to hold the parts in such adjusted position. Moreover, the tube 14 and rod 27 are constructed of relatively soft metal 5 so that they may be bent as at 32 and 33 respectively to position the lighter assembly A properly in a vertical plane relative to the burners. Thus the lighter assembly is capable of substantially universal adjustment 10 relative to the burners and such adjustment may be easily and quickly effected.

While it is believed that from the foregoing description the nature and advantages of the invention will be readily apparent, I 15 desire to have it understood that I do not limit myself to what is herein shown and described and that such changes may be resorted to when desired as fall within the scope of what is claimed.

20 What I claim as my invention is:

The combination with a pair of spaced rods for supporting gas burners, a gas lighter for the burners, and a gas manifold, of a support 25 for the gas lighter including a block slidable longitudinally of one of said rods, a rod projecting from said lighter and adjustable transversely of said block, and a gas supply pipe projecting from said lighter and connected to said manifold.

30 In testimony whereof I affix my signature.

EARL W. ROBERTS.
